(57) **CLAIM**

The ornamental design for a stackable stand, as show and described.

DESCRIPTION

FIG. 1 is a perspective view showing the top, right and front side of a stackable stand which forms my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof; and,

FIG. 7 is a left side elevational view thereof.

The broken lines showing an identical stackable stand are for the purposes of illustrating the environment of the article only and form no part of the claimed design.
